GASEOUS ELECTRIC DISCHARGE LAMP

Wilford J. Winninghoff, South Orange, N. J., assignor to General Electric Vapor Lamp Company, Hoboken, N. J., a corporation of New Jersey

Application February 19, 1932, Serial No. 594,115

2 Claims. (Cl. 176—42)

The present invention relates to electric gaseous discharge devices, and more particularly to mercury vapor lamps and the like.

The invention consists in the new and novel structure and combination of elements, as herein-after set forth and claimed.

A particular object of the invention is to provide a vapor arc lamp which will have improved operating characteristics, and a long useful life. Another object of the invention is to provide a vapor arc lamp in which the arc tube is maintained in a fixed position. Another object of the invention is to provide a vapor arc lamp in which the arc tube is effectively protected by the reflector. A further object of the invention is to provide a vapor arc lamp having no live electrical contacts exposed. Still another object of the invention is to provide a vapor arc lamp all the elements of which operate at a relatively low temperature. Still other objects and advantages of the invention will appear from the following detailed specification, or from an inspection of the accompanying drawings.

In the operation of vapor arc lamps, such as the well known mercury arc lamps of the alternating current type, failures have occasionally been caused by the short circuiting of the anodes. I have found that this short circuiting is caused by a film formed by particles sputtered from the anodes during operation, and particularly during that part of each cycle when the anodes are inactive. I have furthermore found that this sputtering may be very effectively reduced by constricting the entrances to the anode chambers, and by making this constriction relatively long, whereby the diffusion of positive ions to the anodes is appreciably reduced. By a novel arrangement of a bead about the anode inlead I have also found it possible to provide a long surface path between the anodes, a portion of which is substantially shielded from sputtered particles. As a result of these improvements I find that my new lamp is virtually immune to failures due to short circuiting of the anode, despite the relative close spacing of the anodes. I have also found that the reduction or absence of the sputtered film greatly facilitates the initiation of the arc. The novel arrangement of the anode chambers, substantially on the same level as the arc tube, is of special advantage, since it permits these chambers to be placed within the reflector which is commonly used, whereby these chambers are effectively shielded from the breakage so frequently encountered in lamps having the upwardly extending "horns" heretofore in use. Failure of these devices has also occasionally occurred due to the rotation of the arc tube, as the result of excessive vibration or the like, until the inlead to the mercury cathode became exposed, whereupon the arc would transfer to said inlead, with the resulting destruction of the arc tube at the cathode seal. I have discovered that this difficulty may be easily overcome by interlocking the arc tube with the reflector, so as to positively preclude rotation of the arc tube in its clamps. This novel construction also permits the use of a much smaller quantity of mercury for the cathode than has been heretofore practicable, with a corresponding decrease in the cost of the lamp. The smaller quantity of mercury also decreases the hazard heretofore encountered as a result of mercury hammer during the handling of the device. By a novel system of connections I have also provided insulation about all exposed electrical parts, while by housing the ballast resistances within a tight metal container the maximum operating temperature of the exposed parts has been greatly reduced, both of these factors affording further safety in the operation of my new lamp. The insulating connections employed at the anodes also cut down the heat radiation from the anode chambers, with a resulting increase in the temperature of these chambers which prevents the condensation of mercury therein.

For the purpose of illustrating my invention I have shown a preferred embodiment thereof in the accompanying drawings, in which

Fig. 1 is an elevational view, in part section, of a mercury vapor arc lamp of the well known Cooper Hewitt type,

Fig. 2 is a schematic diagram of the same lamp, showing the electrical connections and auxiliary apparatus associated with the arc tube,

Fig. 3 is a plan view, in part section, of the arc tube,

Fig. 4 is an elevational view, in part section, of the same arc tube.

Fig. 5 is an end view, in part section, of the lamp of Fig. 1, showing the interlocking of the arc tube with the reflector,

Fig. 6 is an elevational view, in part section, of the novel resistance unit employed in my new lamp, and

Fig. 7 is a sectional view of one of the insulated terminals used on the wires connecting with said arc tube.

As shown in these drawings the lamp consists of

three main units: an arc tube 1, a reflector 2, and an auxiliary unit 3. Said arc tube 1, which is of any suitable vitreous material, has a spherical bulb 4 at one end thereof, in the bottom of which 5 there is formed a small well 5. Directly over said well 5 there is formed an outwardly extending cup through which is sealed an inlead 6, a screw cap 7 which is fitted over said cup being connected to said inlead. Said inlead extends downwardly to a point within the well 5, being beaded throughout its length except for a short portion thereof near the bottom of said well. A pool of mercury 8, comprising the cathode, fills said well 5 and extends for some distance thereabout within 10 said bulb 4. That part of the inner surface of said bulb which is in contact with the mercury meniscus is preferably coated with carborundum or other granular substance 9 in order to make said mercury meniscus irregular and thereby facilitate starting. This carborundum is preferably held in place by fritting it to the bulb, a convenient method therefor being disclosed in my co-pending application, Serial No. 511,409, filed January 26, 1931. A similar outwardly extending cup 10 is formed in the wall of said bulb opposite the arc tube 1, through which extends a short inlead 11. Said inlead is used only during the so-called "treating" of the lamp during the manufacture thereof, when it is sometimes convenient to operate the tube in a vertical position, hence when completed this inlead is cut off as close as possible on the outside of said cup 10. A conducting sheath 12, which is conveniently formed of overlapping tinfoil sheets, is affixed about the sides 15 of the cup 11, and also about that portion of the bulb 4 which is in proximity to the mercury 8, with a connecting link therebetween, this sheath serving as the well known "starting-band." A screw cap 13 is then placed on the cup 10 in contact with said sheath, but insulated from the inlead 11. A coating of black paint (not shown) is placed over the entire bulb 4, both to increase 20 the heat radiation therefrom, and to conceal the flicker of the arc due to movement of the "hot spot" on the mercury 8.

At the opposite end of the arc tube 1 there are a pair of spherical anode chambers 14 which are connected to said arc tube through the relatively constricted tubes 15. The axes of said tubes 15 are each at an angle, of the order of 22 degrees, with the axis of the arc tube 1, and lie in the plane determined by the axis of said arc tube and a horizontal line which is perpendicular thereto. An inlead 16 is sealed into each of said anode chambers 14 through a reentrant seal at a point opposite the tube 15, an anode 17 being attached to the inner end of each of said inleads. About each of said inleads is a bead 18 which extends from the seal to a point near said anode, an appreciable portion, of the order of at least one fourth of an inch, thereof near said anode being flared slightly, say a millimeter, away from said inlead, in order to provide a relatively long space into which neither the discharge nor sputtered particles can penetrate. A screw cap 19 is attached to each of said anode chambers, the inleads 16 being connected thereto.

Said arc tube is suspended in the proper position in the cylindrical reflector 2 by means of suitable clamps 20, with the screw cap 7 extending upwardly through an opening in said reflector. Mounted on said reflector is the auxiliary unit 3. As shown in Fig. 2 this auxiliary unit comprises 70 an autotransformer 21, two resistance units 22, an

inductance 23, a rectifier 24, a condenser 25, and a shifter 26. Suitable taps on said autotransformer 21 are connected to the line, while the ends thereof are connected through the resistances 22 to a pair of sockets 27 which are screwed onto the caps 19, the leads between said resistances and said sockets passing through a suitable conduit on said reflector, and thence through an opening in said reflector which is adjacent to the anode end of the arc tube 1. The midpoint of said autotransformer is connected through the inductance 23 to another socket 27 which is screwed onto the screw cap 7, said socket loosely fitting in the aforesaid hole in said reflector through which said cap extends, whereby said socket cooperates with said reflector to prevent rotation of the arc tube in said reflector. From a point between said inductance 23 and said socket 27 a connection is made through the shifter 26 to the midpoint of the full-wave rectifier 24, the other terminals of 10 said rectifier being connected to low voltage taps on either side of the midpoint of said autotransformer 21. From a point between said shifter 26 and the rectifier 24 a connection is made through a condenser 25 to another socket 27 which is 15 screwed onto the cap 13. 20

As shown in Fig. 6, the resistances 22 comprise an annular vitreous member 30 having a helical groove in the outer wall thereof, within which is placed a helically wound iron resistor 31, the ends 30 of said resistor being connected to the tip and sleeve of a conventional screw base. A metal cover 32 is placed over the resistor 31, the edge of said cover making a friction fit with a flange on the annular member 30, suitable ears on said cover being used to hold it in place thereon. This construction affords both a large heat radiating surface, with resulting lower operative temperature, and a means for protecting the associated apparatus from damage or failure as a result of a 40 broken resistor 31, which otherwise might uncoil and make undesirable electrical connections.

The sockets 27 are shown in detail in Fig. 7. These sockets comprise a moulded housing 33 of bakelite or the like, within which there is affixed a threaded sleeve 34. The insulated lead wire 35 extends through a tubular part of the housing 33, the end thereof being stripped and soldered to a contact making member 36 which fits within the end of the sleeve 34. A flanged sleeve 37 is 50 crimped down onto said lead just outside of the housing 33, whereby the various parts of the socket are locked in place, while a similar flanged sleeve 38, reversed, extends into the tubular part of said housing, and serves as a bushing to permit free rotation of said housing 33 and sleeve 34 on said lead 35. These sockets are easily attached, and fully insulate all live parts of the arc tube 1. Even more important, however, is the fact that the sockets 27 which are connected 60 to the caps 19 also serve to materially decrease the escape of heat from the anode chambers 14, with the result that these chambers operate at a temperature which is sufficient to prevent the condensation of mercury therein, thus permitting the use of the highly desirable anode arrangement illustrated.

In the operation of this device, the arc is initiated by producing a voltage surge on the starting band 12 according to the method disclosed in Patent 2,001,517, granted May 14, 1935 to Leroy J. Buttolph, this being a most effective means for producing the arc. The condenser 25, which is used to insulate the starting band 12, offers little impedance to this surge but per- 75

mits the passage of virtually no energy at the usual frequency of 60 cycles or less. Due to the interlocking of the arc tube 1 with the reflector 2, by means of the cathode inlead assembly, there is no danger of the tube rotating in its supports 5, hence I find it possible to reduce the mercury employed to substantially a third of that which has heretofore been considered necessary for safety. This novel arrangement of the cathode 10 inlead is also desirable, since it avoids virtually all danger of mechanical breakage, during handling, cleaning, and the like. At the opposite end of the tube the anode arrangement is extremely conductive to long life of the tube. 15 Due to the constricted tubes 15, which I find it advisable to make say three-eighths to one-half inch long, and of say one-half inch diameter, where the main arc tube is fifty inches long and an inch in diameter, there is very little material 20 sputtered from the anodes at any time. Hence the formation of a conducting film on the wall of said anode chambers is almost entirely eliminated. By using a reentrant seal, as shown, for the anode leads 16 the surface path which must 25 be covered by this film is materially increased, with a corresponding reduction in the possibility of short circuit due to this film. Even more effective for this purpose is the arrangement of the bead 18, since by making the spacing between said lead and the flare on said bead small 30 virtually no material can be sputtered onto the inside of the flare, nor can the discharge attach itself to the inlead therein. As a result my new lamp is virtually immune to failure by anode 35 short circuiting. The hazard of breaking these anodes is also materially reduced by their new location with respect to the arc tube, since they are now effectively shielded by the reflector 2. The aforesaid reduction in the sputtered film 40 also facilitates the starting of the arc. This is due to the fact that such a film tends to hold globules of condensed mercury, and if the film is in contact with either anode these globules can serve as a cathode, drawing the arc thereto 45 instead of to the main cathode. In such a case the main arc can not be initiated until these mercury globules have been evaporated. Due to the elimination of this condition the probability of the initiation of the main arc upon the application of the first voltage surge is vastly increased. 50

While I have described my invention by reference to a specific embodiment thereof, it is to be understood that it is not limited thereto, but that 55 various changes, substitutions or omissions,

within the scope of the appended claims, may be made therein without departing from the spirit of my invention.

I claim as my invention:—

1. A gaseous discharge lamp having an elongated luminous arc tube having two bulbous anode chambers connected to one end thereof through relatively constricted tubular throats, a cup shaped anode in each of said chambers facing said throat, said throats each having a diameter and a length equal to the diameter of said anodes, the axes of said throats being at an angle to the axis of said tube in the plane determined by said axis and a horizontal line which is perpendicular thereto, a cathode bulb at the opposite end of said tube having a well extending from the bottom thereof, a pool of mercury in said cathode bulb, an inlead sealed through the top of said cathode bulb and extending downwardly into said well, said inlead being enclosed within an insulating sheath to a point below the level of said mercury, and a conducting sheath on the outside of said cathode bulb in electrostatic relation to said pool. 10 15 20

2. A mercury lamp comprising a trough reflector, a straight luminous arc tube, means to support said arc tube within the curvature of said reflector, said arc tube having two bulbous anode chambers connected to one end thereof through relatively constricted tubular throats, a cup shaped anode in each of said chambers facing said throat, said throats each having a diameter and a length equal to the diameter of said anodes, the axes of said throats being at an angle to the axis of said tube in the plane determined by said axis and a horizontal line which is perpendicular thereto, a cathode bulb at the opposite end of said tube having a well extending from the bottom thereof, a pool of mercury within said cathode bulb, an inlead sealed through the top of said bulb and extending downwardly into said well, said inlead being enclosed within an insulating sheath to a point below the level of said mercury, a conducting sheath on the outside of said bulb in electrostatic relation to said pool, a terminal on the top of said cathode bulb connected to said inlead, and a connector attached to said terminal which passes through an opening in said reflector, said connector having an insulating sheath which fits said opening, 40 45 50 whereby said tube cannot be rotated within said reflector to move said inlead out of contact with said pool.

WILFORD J. WINNINGHOFF.
